UNITED STATES PATENT OFFICE

2,477,132

ELECTRIC BALLAST

Robert F. Rowe, Fort Wayne, Ind., assignor to
General Electric Company, a corporation of
New York

Application December 22, 1945, Serial No. 637,027

2 Claims. (Cl. 240—51.12)

1

This invention relates to electric ballasts and more particularly to improvements in ballasts for fluorescent lamps.

Fluorescent lamps, being electric discharge devices with a negative resistance characteristic, require a ballast in their circuits. There are a wide variety of styles of fluorescent lamps and an even greater variety of fixtures for supporting such lamps. A form of fluorescent lamp which it is expected will be used in large numbers consists of a circular arrangement of the fluorescent lamp tube so that its two ends, each of which ordinarily contains a filament, are close together and can be fitted into the same socket. Such a circular lamp may be used in ceiling fixtures or wall fixtures or in portable lamps of either the floor or table variety. One of the problems associated with such lamps and lamp fixtures is the construction of as nearly a universal ballast as is possible. By "universal ballast" is meant a ballast which can be used easily, simply and inexpensively in any and all types of fixtures for either exposed or concealed mountings.

In accordance with this invention there is provided a universal ballast which is characterized by a smooth, attractive, unbroken exterior surface which has no mounting feet or lugs. Provision for mounting this ballast consists of a straight opening or hole which passes entirely through it from one side to the other. This hole is of sufficient diameter to receive an ordinary standard three-eighths inch threaded pipe such as is commonly used in house wiring for conduit and supporting purposes and which fits the threads on standard house wiring devices, such as outlet boxes and the various kinds of adapters. The ballast is also disk-shaped so that it will fit readily into the base of floor and table lamps and can also be used easily in wall and ceiling fixtures. Furthermore, in many cases it can be mounted inside the circular lamp tube so as to provide a very compact installation.

An object of the invention is to provide a new and improved electric ballast.

Another object of the invention is to provide a new and improved combination of ballast and lamp fixture.

A further object of the invention is to provide a new and improved fluorescent lamp construction.

The invention will be better understood from the following description taken in connection with the accompanying drawing and its scope will be pointed out in the appended claims.

In the drawing Fig. 1 is a perspective view

of a preferred form of ballast constructed in accordance with this invention. Fig. 2 is a sectional view of the ballast housing, Fig. 3 is an exploded view of the ballast housing, Fig. 4 is a phantom view of one suitable interior arrangement of the ballast, Fig. 5 is a floor lamp with the ballast mounted in its base, Fig. 6 is a circuit diagram showing how a ballast having the elements shown in Fig. 4 may be connected to a supply line and a single lamp, and Fig. 7 is a ceiling or wall fixture with the ballast mounted therein.

Referring now to the drawing and more particularly to Fig. 1, the ballast is shown as a disk-shaped housing 1 consisting of two principal parts which are a relatively deep circular pan-shaped casing member 2 and a circular flanged base member 3. Passing entirely through the ballast from one flat side to the other is a central mounting hole 4. The bottom of the casing 10 is also provided with a smaller hole 5 through which extend three leads 6, 7 and 8 for the electrical elements of the ballast.

As shown in Fig. 2, the relatively small opening 5 is extruded inwardly and the extruded portions are turned over so as to form a smooth eyelet 9 for the leads. It will also be seen that the central openings, in the bottom of the casing 2 and in the base 3, are surrounded by indented portions 10 and 11 respectively. A tubular eyelet 12 is passed through the central opening in the bottom of the cover 2 and this eyelet is provided with an outwardly turned flange 13 which fits into the indented portion 10 so as to be flush with the outer surface of the casing 2. The other end of the tubular eyelet 12 is long enough so that it can be spun over or turned over to form a flange 14 which lies in the indented portion 11 so as to form a flush clamping or locking means for holding the base 3 securely to the casing 2.

If desired, a tubular spacer 15 may be slipped over the shank of the eyelet 12 so as to provide the proper spacing between the bottom of the casing and the base 3. However, when the housing is filled with insulating compound it usually is not necessary to have the spacer 15.

Fig. 3 clearly shows the four major parts 2, 3, 12 and 15 axially aligned and separated for showing how they may be assembled. The flange 13 of the eyelet 12 may be provided with small projections 16 on its inner surface by means of which the flange 13 can be projection welded to the indentation 10 in the bottom of the casing 2. After the eyelet 12 has been put into place the spacer 15, if used, may be slipped into place

over the eyelet and then the base fitted on and the outer end of the eyelet turned over into the indentation 11 and flush with the remaining surface of the base 3.

A simple ballast for a single lamp usually consists of a transformer-reactor combination, a well-known form of which is shown in Fig. 4 as comprising an autotransformer having a core-type core 17 with coils 18 and 19 on its two winding legs. The reactor part of the ballast may comprise a shell-type core 20 with a winding 21 on its central winding leg.

The remaining spaces in the ballast not occupied by the above-described electrical parts are preferably filled with insulating compound. This securely anchors the electrical parts in place and makes the ballast strong enough to resist large clamping forces between its opposite sides.

One of many practical applications of my improved ballast is shown in Fig. 5, which illustrates a portable floor lamp consisting essentially of the usual base 22, stem 23, and shade 24. Mounted on a suitable holder 25 near the top of the stem 23 is a circular fluorescent lamp 26.

The stem 23 is conventionally threaded into the base 22 and it is shown as extending sufficiently into the base so that it may extend through the central opening 4 in the ballast 1 which has been slid over it with its base 3 against the underside of the base 22 of the lamp. A nut 27 is threaded onto the end of the stem 23 for securely clamping the ballast 1 in place. A line lead 28 extends through a suitable opening in the side of the base 22 and its conductors are connected to the wire leads of the ballast and to a number of leads 29 which extend up through the stem 23 which is, of course, hollow and thus acts both as a support and as a conduit for the leads 29.

The electrical parts shown in Figs. 4 and 5 may actually be connected as shown in Fig. 6 in which the three coils 18, 19 and 21 are connected in series, the coil 18 being the primary winding of the autotransformer to whose terminals the conductors of the input lead 28 are connected. The lamp 26 and reactor 21 are connected in series across the secondary winding of the autotransformer, that is to say, across the coils 18 and 19 in series with each other.

As shown in Fig. 7, the invention is also very well adapted for use in ceiling and wall fixtures, especially fixtures for circular fluorescent lamps. While Fig. 7 illustrates a ceiling fixture, it will be obvious that by rotating the drawing ninety degrees, it also illustrates a wall fixture. In this figure, an incoming conduit 30 extends through a conventional ceiling or wall 31. A backing nut 32 is screwed on the conduit flush with the ceiling or wall leaving the conduit extending a short distance beyond the backing nut. A ceiling or wall plate 33 is then placed over the conduit and the ballast 1 is then slipped over the conduit and a lock nut 34 is screwed on to the conduit and tightened so as to hold the plate and ballast firmly to the ceiling or wall. Connections are then made to the incoming conduit wires, the ballast wires and the wires from a lamp holder 35. A housing 36 which carries the lamp holder 35 and a starter socket 37, already attached and wired, and a starter 38 inserted in the starter socket 37, is then mounted and held in place with screws which attach it to the plate 33; a circular fluorescent lamp 39 can then be inserted in the holder.

Here again it will be seen that the ballast 1 is very easily attached to the fixture without any separate mounting means other than the means

which holds the fixture itself in place and that it conforms to the general shape of the fixture and requires but a minimum increase in the dimension of the fixture in any direction.

While there have been shown and described particular embodiments of this invention, it will be obvious to those skilled in the art that various changes and modifications can be made therein without departing from the invention and, therefore, it is aimed in the appended claims to cover all such changes and modifications as fall within the true spirit and scope of the invention.

What I claim as new and desire to secure by Letters Patent of the United States is:

15. A ballast housing for electric discharge devices comprising, in combination, a relatively deep pan-shaped casing of circular cross section, a pair of openings in the bottom of said pan-shaped casing, one of said openings being concentric with the circular cross section of said casing and being concentrically surrounded by an indented portion of the bottom of said casing, the other of said openings being relatively small, electrical apparatus in said housing having wire leads extending through the smaller of said openings, a cylindrical eyelet passed through the central opening in the bottom of said casing, said eyelet having a flange which is on one end thereof and which lies in said indented portion of the bottom of said casing so as to be flush with the outside surface of the bottom of said casing, said eyelet extending into said casing a distance slightly greater than the height of said casing, and a circular base member having a flanged edge for engaging the sides of said casing member and having a centrally located opening for receiving the other end of said eyelet, the area of said base member surrounding its centrally located opening being indented, said other end of the eyelet being rolled over to form a flange which lies in the indented portion of said base member so as to be flush with the outer surface of said base member for permanently fastening said casing and base members together.
20. 2. A ballast housing for electric discharge devices comprising, in combination, a relatively deep pan-shaped casing of circular cross section, a pair of openings in the bottom of said pan-shaped casing, one of said openings being concentric with the circular cross section of said casing and being concentrically surrounded by an indented portion of the bottom of said casing, the other of said openings being relatively small, electrical apparatus in said housing having wire leads extending through the smaller of said openings, a cylindrical eyelet passed through the central opening in the bottom of said casing, said eyelet having a flange which is on one end thereof and which lies in said indented portion of the bottom of said casing so as to be flush with the outside surface of the bottom of said casing, said eyelet extending into said casing a distance slightly greater than the height of said casing, a cylindrical spacer sleeve fitted over said eyelet, said spacer sleeve being shorter than said eyelet, and a circular base member having a flanged edge for engaging the sides of said casing member and having a centrally located opening for receiving the other end of said eyelet, the area of said base member surrounding its centrally located opening being indented, said other end of said eyelet being rolled over to form a flange which lies in the indented portion of said base member so as to be flush with the outer surface of said
25. 3. A ballast housing for electric discharge devices comprising, in combination, a relatively deep pan-shaped casing of circular cross section, a pair of openings in the bottom of said pan-shaped casing, one of said openings being concentric with the circular cross section of said casing and being concentrically surrounded by an indented portion of the bottom of said casing, the other of said openings being relatively small, electrical apparatus in said housing having wire leads extending through the smaller of said openings, a cylindrical eyelet passed through the central opening in the bottom of said casing, said eyelet having a flange which is on one end thereof and which lies in said indented portion of the bottom of said casing so as to be flush with the outside surface of the bottom of said casing, said eyelet extending into said casing a distance slightly greater than the height of said casing, a cylindrical spacer sleeve fitted over said eyelet, said spacer sleeve being shorter than said eyelet, and a circular base member having a flanged edge for engaging the sides of said casing member and having a centrally located opening for receiving the other end of said eyelet, the area of said base member surrounding its centrally located opening being indented, said other end of said eyelet being rolled over to form a flange which lies in the indented portion of said base member so as to be flush with the outer surface of said
30. 4. A ballast housing for electric discharge devices comprising, in combination, a relatively deep pan-shaped casing of circular cross section, a pair of openings in the bottom of said pan-shaped casing, one of said openings being concentric with the circular cross section of said casing and being concentrically surrounded by an indented portion of the bottom of said casing, the other of said openings being relatively small, electrical apparatus in said housing having wire leads extending through the smaller of said openings, a cylindrical eyelet passed through the central opening in the bottom of said casing, said eyelet having a flange which is on one end thereof and which lies in said indented portion of the bottom of said casing so as to be flush with the outside surface of the bottom of said casing, said eyelet extending into said casing a distance slightly greater than the height of said casing, a cylindrical spacer sleeve fitted over said eyelet, said spacer sleeve being shorter than said eyelet, and a circular base member having a flanged edge for engaging the sides of said casing member and having a centrally located opening for receiving the other end of said eyelet, the area of said base member surrounding its centrally located opening being indented, said other end of said eyelet being rolled over to form a flange which lies in the indented portion of said base member so as to be flush with the outer surface of said
35. 5. A ballast housing for electric discharge devices comprising, in combination, a relatively deep pan-shaped casing of circular cross section, a pair of openings in the bottom of said pan-shaped casing, one of said openings being concentric with the circular cross section of said casing and being concentrically surrounded by an indented portion of the bottom of said casing, the other of said openings being relatively small, electrical apparatus in said housing having wire leads extending through the smaller of said openings, a cylindrical eyelet passed through the central opening in the bottom of said casing, said eyelet having a flange which is on one end thereof and which lies in said indented portion of the bottom of said casing so as to be flush with the outside surface of the bottom of said casing, said eyelet extending into said casing a distance slightly greater than the height of said casing, a cylindrical spacer sleeve fitted over said eyelet, said spacer sleeve being shorter than said eyelet, and a circular base member having a flanged edge for engaging the sides of said casing member and having a centrally located opening for receiving the other end of said eyelet, the area of said base member surrounding its centrally located opening being indented, said other end of said eyelet being rolled over to form a flange which lies in the indented portion of said base member so as to be flush with the outer surface of said
40. 6. A ballast housing for electric discharge devices comprising, in combination, a relatively deep pan-shaped casing of circular cross section, a pair of openings in the bottom of said pan-shaped casing, one of said openings being concentric with the circular cross section of said casing and being concentrically surrounded by an indented portion of the bottom of said casing, the other of said openings being relatively small, electrical apparatus in said housing having wire leads extending through the smaller of said openings, a cylindrical eyelet passed through the central opening in the bottom of said casing, said eyelet having a flange which is on one end thereof and which lies in said indented portion of the bottom of said casing so as to be flush with the outside surface of the bottom of said casing, said eyelet extending into said casing a distance slightly greater than the height of said casing, a cylindrical spacer sleeve fitted over said eyelet, said spacer sleeve being shorter than said eyelet, and a circular base member having a flanged edge for engaging the sides of said casing member and having a centrally located opening for receiving the other end of said eyelet, the area of said base member surrounding its centrally located opening being indented, said other end of said eyelet being rolled over to form a flange which lies in the indented portion of said base member so as to be flush with the outer surface of said
45. 7. A ballast housing for electric discharge devices comprising, in combination, a relatively deep pan-shaped casing of circular cross section, a pair of openings in the bottom of said pan-shaped casing, one of said openings being concentric with the circular cross section of said casing and being concentrically surrounded by an indented portion of the bottom of said casing, the other of said openings being relatively small, electrical apparatus in said housing having wire leads extending through the smaller of said openings, a cylindrical eyelet passed through the central opening in the bottom of said casing, said eyelet having a flange which is on one end thereof and which lies in said indented portion of the bottom of said casing so as to be flush with the outside surface of the bottom of said casing, said eyelet extending into said casing a distance slightly greater than the height of said casing, a cylindrical spacer sleeve fitted over said eyelet, said spacer sleeve being shorter than said eyelet, and a circular base member having a flanged edge for engaging the sides of said casing member and having a centrally located opening for receiving the other end of said eyelet, the area of said base member surrounding its centrally located opening being indented, said other end of said eyelet being rolled over to form a flange which lies in the indented portion of said base member so as to be flush with the outer surface of said
50. 8. A ballast housing for electric discharge devices comprising, in combination, a relatively deep pan-shaped casing of circular cross section, a pair of openings in the bottom of said pan-shaped casing, one of said openings being concentric with the circular cross section of said casing and being concentrically surrounded by an indented portion of the bottom of said casing, the other of said openings being relatively small, electrical apparatus in said housing having wire leads extending through the smaller of said openings, a cylindrical eyelet passed through the central opening in the bottom of said casing, said eyelet having a flange which is on one end thereof and which lies in said indented portion of the bottom of said casing so as to be flush with the outside surface of the bottom of said casing, said eyelet extending into said casing a distance slightly greater than the height of said casing, a cylindrical spacer sleeve fitted over said eyelet, said spacer sleeve being shorter than said eyelet, and a circular base member having a flanged edge for engaging the sides of said casing member and having a centrally located opening for receiving the other end of said eyelet, the area of said base member surrounding its centrally located opening being indented, said other end of said eyelet being rolled over to form a flange which lies in the indented portion of said base member so as to be flush with the outer surface of said
55. 9. A ballast housing for electric discharge devices comprising, in combination, a relatively deep pan-shaped casing of circular cross section, a pair of openings in the bottom of said pan-shaped casing, one of said openings being concentric with the circular cross section of said casing and being concentrically surrounded by an indented portion of the bottom of said casing, the other of said openings being relatively small, electrical apparatus in said housing having wire leads extending through the smaller of said openings, a cylindrical eyelet passed through the central opening in the bottom of said casing, said eyelet having a flange which is on one end thereof and which lies in said indented portion of the bottom of said casing so as to be flush with the outside surface of the bottom of said casing, said eyelet extending into said casing a distance slightly greater than the height of said casing, a cylindrical spacer sleeve fitted over said eyelet, said spacer sleeve being shorter than said eyelet, and a circular base member having a flanged edge for engaging the sides of said casing member and having a centrally located opening for receiving the other end of said eyelet, the area of said base member surrounding its centrally located opening being indented, said other end of said eyelet being rolled over to form a flange which lies in the indented portion of said base member so as to be flush with the outer surface of said
60. 10. A ballast housing for electric discharge devices comprising, in combination, a relatively deep pan-shaped casing of circular cross section, a pair of openings in the bottom of said pan-shaped casing, one of said openings being concentric with the circular cross section of said casing and being concentrically surrounded by an indented portion of the bottom of said casing, the other of said openings being relatively small, electrical apparatus in said housing having wire leads extending through the smaller of said openings, a cylindrical eyelet passed through the central opening in the bottom of said casing, said eyelet having a flange which is on one end thereof and which lies in said indented portion of the bottom of said casing so as to be flush with the outside surface of the bottom of said casing, said eyelet extending into said casing a distance slightly greater than the height of said casing, a cylindrical spacer sleeve fitted over said eyelet, said spacer sleeve being shorter than said eyelet, and a circular base member having a flanged edge for engaging the sides of said casing member and having a centrally located opening for receiving the other end of said eyelet, the area of said base member surrounding its centrally located opening being indented, said other end of said eyelet being rolled over to form a flange which lies in the indented portion of said base member so as to be flush with the outer surface of said
65. 11. A ballast housing for electric discharge devices comprising, in combination, a relatively deep pan-shaped casing of circular cross section, a pair of openings in the bottom of said pan-shaped casing, one of said openings being concentric with the circular cross section of said casing and being concentrically surrounded by an indented portion of the bottom of said casing, the other of said openings being relatively small, electrical apparatus in said housing having wire leads extending through the smaller of said openings, a cylindrical eyelet passed through the central opening in the bottom of said casing, said eyelet having a flange which is on one end thereof and which lies in said indented portion of the bottom of said casing so as to be flush with the outside surface of the bottom of said casing, said eyelet extending into said casing a distance slightly greater than the height of said casing, a cylindrical spacer sleeve fitted over said eyelet, said spacer sleeve being shorter than said eyelet, and a circular base member having a flanged edge for engaging the sides of said casing member and having a centrally located opening for receiving the other end of said eyelet, the area of said base member surrounding its centrally located opening being indented, said other end of said eyelet being rolled over to form a flange which lies in the indented portion of said base member so as to be flush with the outer surface of said
70. 12. A ballast housing for electric discharge devices comprising, in combination, a relatively deep pan-shaped casing of circular cross section, a pair of openings in the bottom of said pan-shaped casing, one of said openings being concentric with the circular cross section of said casing and being concentrically surrounded by an indented portion of the bottom of said casing, the other of said openings being relatively small, electrical apparatus in said housing having wire leads extending through the smaller of said openings, a cylindrical eyelet passed through the central opening in the bottom of said casing, said eyelet having a flange which is on one end thereof and which lies in said indented portion of the bottom of said casing so as to be flush with the outside surface of the bottom of said casing, said eyelet extending into said casing a distance slightly greater than the height of said casing, a cylindrical spacer sleeve fitted over said eyelet, said spacer sleeve being shorter than said eyelet, and a circular base member having a flanged edge for engaging the sides of said casing member and having a centrally located opening for receiving the other end of said eyelet, the area of said base member surrounding its centrally located opening being indented, said other end of said eyelet being rolled over to form a flange which lies in the indented portion of said base member so as to be flush with the outer surface of said
75. 13. A ballast housing for electric discharge devices comprising, in combination, a relatively deep pan-shaped casing of circular cross section, a pair of openings in the bottom of said pan-shaped casing, one of said openings being concentric with the circular cross section of said casing and being concentrically surrounded by an indented portion of the bottom of said casing, the other of said openings being relatively small, electrical apparatus in said housing having wire leads extending through the smaller of said openings, a cylindrical eyelet passed through the central opening in the bottom of said casing, said eyelet having a flange which is on one end thereof and which lies in said indented portion of the bottom of said casing so as to be flush with the outside surface of the bottom of said casing, said eyelet extending into said casing a distance slightly greater than the height of said casing, a cylindrical spacer sleeve fitted over said eyelet, said spacer sleeve being shorter than said eyelet, and a circular base member having a flanged edge for engaging the sides of said casing member and having a centrally located opening for receiving the other end of said eyelet, the area of said base member surrounding its centrally located opening being indented, said other end of said eyelet being rolled over to form a flange which lies in the indented portion of said base member so as to be flush with the outer surface of said

base member for permanently fastening said casing and base members together.
